INVENTOR

WILLIAM I. BROWN.

By Riley, Robinson & Lovr

ATTORNEY'S.

UNITED STATES PATENT OFFICE.

WILLIAM I. BROWN, OF UTICA, NEW YORK, ASSIGNOR TO THE THISTLE CHEESE COMPANY, OF SAME PLACE.

DESIGN FOR A CHEESE.

SPECIFICATION forming part of Design No. 26,312, dated November 17, 1896.

Application filed June 23, 1896. Serial No. 596,658. Term of patent 3½ years.

To all whom it may concern:

Be it known that I, WILLIAM I. BROWN, a citizen of the United States, residing at Utica, in the county of Oneida and State of New York, have invented and produced a new and original Design for a Cheese, of which the following is a specification, reference being had to the accompanying drawings, showing the same.

Figure 1 shows in perspective my design for a cheese. Fig. 2 shows the same partially turned to exhibit other sides. Fig. 3 shows a longitudinal section of the cheese.

The feature of my design is the general form of outline, as shown in connection with

the several transverse indented straight grooves extending across two opposite sides of the cheese only and disposed opposite to each other, as shown, and all constituting a unitary design.

What I claim is—

The design for a cheese as herein shown and described.

In witness whereof I have affixed my signature in presence of two witnesses.

WILLIAM I. BROWN.
